UNITED STATES PATENT OFFICE.

RAYMOND BARKHURST, OF PORTLAND, OREGON.

ORE MILL.

Application filed February 11, 1924. Serial No. 692,056.

To all whom it may concern:

Be it known that I, RAYMOND BARKHURST, a citizen of the United States, residing at Portland, in the county of Multnomah and 5 the State of Oregon, and having my address at 94 6th Street, in said city and State, have invented a new and useful Ore Mill, of which the following is a specification.

My invention relates to improvements in 10 ore mills wherein mineral bearing ores are fed into the mill and are reduced to fineness through the action of a series of balls caused to rotate in ball races, the balls being under pressure as rotated. The ore to be 15 ground is fed into a hopper together with an amount of water that is sufficient for grinding purposes, the amount required depending upon the character of the ore to be reduced. The hopper, or chute deposits the 20 ore, at a location, within the inner circumference of the race and as the ore is reduced it gravitates to a lower level where a second series of balls are located and operating in a second race, the second series of 25 balls also under pressure and being driven through contact with a ring riding atop of the balls. The ore as reduced passes across the balls' circumferential path and that portion that floats and has been reduced to a 30 sufficient fineness is permitted to be drawn off through a central location in the form of slimes through a screen. The height at which the same flows from the grinding chamber may be adjusted to meet the working 35 conditions, and the character of the material being reduced. The drawing off of the ground and reduced material through a central location accomplishes the result of the materials flowing off as slimes at the 40 point of least agitation within the reduction mill and, therefore, permits of the settling of those materials of a high specific gravity within the mill at which point they may be drawn off, or recovered at desired times.

Further objects of my invention are an 45 ore mill of simplified design having all parts accessible for adjustment and repair, or replacement, and one that is easily assembled and that may be transported in small units 50 and assembled at the point of use, which

many times is at locations distant from standard means of transportation.

I attain these objects by the mechanism illustrated in the accompanying drawings, in which—

Fig. 1 is a section view of the assembled machine, or mill, and Fig. 2 is a plan view of the same. Fig. 3 is a plan view of the lower, or bottom raceway and Fig. 4 is a section view of the same taken on line 4—4 of 60 Fig. 3. Fig. 5 is a section view of the lower part of the outlet leading from the grinding bowl of the mill and is made to show in detail the construction of the adjustable feature, and to show a riffle and mercury pocket 65 for the catching of any material of a high specific gravity that may have floated from the grinding bowl.

Similar reference characters refer to similar parts throughout the several views. 70

1 is the base of the grinding bowl that may be supported in any convenient manner such as upon leg supports, a concrete foundation, masonry underpinning or any other form of foundation, upon the upper side 75 of this bowl is a circumferential groove into which ball race ring 2 is fitted as a wearing ring for the balls to rotate upon. An annular groove 3 is placed upon the upper side of this ring and having one or more openings 4 leading therefrom and to which valves 4^a may be attached. In this race way may be placed mercury, or other suitable composition to act as a settling basin 80 for material possessing a higher specific 85 gravity than that of the mercury or other composition. 5 are grinding balls operating within the race way of the race ring and 6 is a double race ring which acts as the driving agent for the rotation of the balls 90 within the race way. In order to facilitate rapid grinding and to prevent centrifugal force from throwing these balls out of the races it is necessary to apply pressure to the balls when the ore mill is operated at 95 commercial speeds. The double race ring 6 is secured to the cylinder 7 having cylinder head 8 with vent holes 9 in the head of the same. The object of vent holes is to prevent a vacuum forming, or the creation of a pres- 100

sure within the cylinder. 10 is a driving shaft, this driving shaft may be secured to the double race ring directly in some mills embodying my construction but I have here shown the cylinder and cylinder head construction as a means of securing the same to the driving shaft. As these mills are used for the crushing of the hardest materials a certain flexibility must obtain and to make this possible the driving shaft is mounted upon a bearing wherein a long key slides. This may be within the connection at the cylinder head or at some other point. To provide a convenient means for the lifting of the driving head from the grinding bowl, this key way may be placed within the cylinder head and the whole mechanism lifted out by the application of a lifting moment to screw eye 10. 11 is a universal joint, 12 a stub shaft, 13 a vertical bearing and 14 a driving pulley for the application of a suitable frictional drive to the same. 15 is a race pressure ring to which the pressure is initially applied which is in turn applied to all of the balls in the mill and this ring has a race in it also. In order that a pressure may be applied to this ring it is quite essential that the ring should not rotate with the drive and to prevent this I have provided a locating split lug 17 and the presser bar 16 connects the same with the race pressure ring. The pressure may be applied through a spring action or live rubber as shown at 19. 20 is the mill cylinder and 21 are amalgam plates placed on the inner periphery of the mill shell and the same are made corrugated to break up the swirling action of the semiliquid material that is caused by the rapid rotation of the grinding mechanisms. I have provided an inner discharge from the mill and to retain the material remaining in the grinding bowl until a specified degree of fineness has been obtained I have placed a screen 22 over the discharge pipe. This screen accomplishes the further purpose of preventing a swirling action of the liquid at the point directly above the discharge pipe and will cause a constant discharged amount to flow from the grinding bowl if the input is a constant. As these mills are primarily designed for the reduction of mineral bearing ores and the recovery of the values contained therein a settling basin 22^a is provided within the screened area and about the discharge pipe. A second settling basin is also provided in the outflow pipe. The grinding of different materials will require that the point of discharge or height of the discharge pipe will be required to be raised or lowered as the work progresses. The discharge pipe 23 passes through the base of the mill and a tight joint is maintained at the point by an adjustable gland. 24, 25 is a T having a cap

26 encasing the head 28 of the adjusting screw 27 for the raising or lowering of the discharge pipe 23 through the action of hand screw 33. 29 is a baffle plate placed in the outward discharge flow of the material from the reduction mill placed across the settling basin 30 that may be filled with mercury or other liquid material of a high specific gravity and 31 is a suitable screw connection for the valve 32 to be attached thereto. The material to be reduced is fed into the grinding bowl by means of a suitable chute and is deposited into the space within the inner circumference of the upper ring of balls as shown at 34 and it gravitates from there to the space 35 and centrifugal force causes the heavier material to be thrown against the amalgam plates 21 and from there the uncollected unground material again finds its way into the path of the lower series of balls. These balls being at the lower point of the mill all materials are here reduced to the desired fineness and will then float into the space 36 and be carried from there to the exterior of the mill.

Having thus described my invention in such detail that any one may build the same I wish to make the following claims therefor—

1. An ore mill comprising a base having a renewable ring race therein, balls within the race, a driven ring resting upon the balls with an annular race upon its upper surface, balls in the upper race and flexible means for applying pressure to the aforesaid balls, a cylindrical shell secured to the base, an amalgam corrugated cylindrical shell adapted to being placed within the cylindrical shell, a central overflow through the base adapted to regulating the height of the overflow above the base and a base support.

2. An ore mill comprising a base adapted to a base support, an annular ring race upon its upper face, an annular ring fitted to the ring race, a ball race in the upper surface of the ring, an annular groove within the race-way, one or more passageways leading from the groove to the exterior of the base through the base, valve connections with the passageways, a central liquid overflow through the base, means for changing the height of the overflow, and a screen cover over the central overflow limiting the coarseness of material to be discharged.

3. An ore mill comprising a base, a cylindrical shell secured to the base, a ball race within the base, balls operable within the race, a driven ring having ball races upon its upper and lower face said races having balls adapted to being driven by said races, flexible pressure means for applying pressure upon the driven balls, a centrally positioned overflow adapted to a change of

height of overflow, and a strainer means positioned around the overflow to regulate the degree of coarseness to be discharged.

4. An ore mill comprising a base, a shell secured to the base, renewable annular races and balls operable therein under pressure and means for driving the balls under pressure, a corrugated amalgam plate adjacent

the inner circumference of the shell, a centrally located discharge through the base, ¹⁰ means for regulating the degree of coarseness of the material discharged therethrough and amalgam pockets in the line of discharge and means for tapping the same.

RAYMOND BARKHURST.
